UNITED STATES PATENT OFFICE.

SAMUEL R. FRAIM, OF LANCASTER, PENNSYLVANIA.

PADLOCK.

Application filed May 10, 1928. Serial No. 276,781.

This invention relates in general to padlocks and more particularly to improvements in the mechanism of padlocks of the type disclosed in the United States patent issued to myself and relating to Padlocks No. 1,563,181, November 24, 1925.

Among other objects of my invention is that of providing a positive locking mechanism to comprise two main locking units, 10 each being capable of securely fastening the shackle within the padlock casing; one locking unit to engage the removable toe of the shackle, and the other locking unit to engage the toe as well as the pivoted heel of the 15 shackle to effect a double locking of the padlock.

Another object of the invention is to so construct the locking units that they will be actuated in sequence in that unlocking same 20 one will be completely withdrawn from locked position before the other is actuated, and that the latter must be operated before the toe is disengaged, and moreover fully actuated by the key before the heel is disengaged and the toe is free to be withdrawn 25 from the casing.

A further object is to so construct and arrange the locking units that there will be no occurrence of malfunctioning due to undesired relative motion, or other disarrangement, or lack of return spring action.

With the foregoing and other objects in view, the invention consists in the combination of parts and in the details of construction hereinafter set forth, certain embodiments thereof being illustrated in the accompanying drawings, in which:

Figure 1 is a top plan view of the padlock with the upper plate of the casing removed 40 and locking mechanism locked;

Figure 2 is a similar view showing a partial key action with the locking mechanism partially unlocked, namely the pivoted lever;

Figure 3 is a similar view showing the locking mechanism completely unlocked and the shackle released;

Figure 4 is a view similar to Figure 3 with the lever and change plate removed;

Figure 5 is a view in section taken along line 5—5 of Figure 1;

Figure 6 is a view of all the working elements of the assembly disassembled as well

as the key, each being shown in detail in perspective.

Referring more particularly to the drawings, the device comprises a casing, the lower half of which is shown in the drawings at 1, in which there is located a stud 2 upon which a shackle 3 is pivotally mounted so 60 as to allow the toe 5 of the shackle to be swung into and out of the casing.

The mechanism for locking the shackle to the casing consists mainly in a pivoted lever 9 and a slidably mounted bolt 10, each of 65 which is adapted to engage opposite sides of the toe 5 of the shackle in locked relation. The lever 9 is pivotally mounted on the casing stud 11 and is normally spring-actuated against the casing stud 17 by means of the 70 spring 21. This spring 21 is coiled about the stud 7 and bears against the casing wall and against a stud 22 carried by the lever 9 on the under side thereof. The lever 9 also carries an additional stud 36 whose sole purpose is that of a bearing member for alignment in the operation of the lever. The lever is further provided with a lug 12 on the upper side thereof, the purpose of which lug will appear later.

The bolt 10 is mounted on the stud 17 which fits in an elongated slot 16 formed in the bolt, thereby adapting the bolt for sliding and rotary movement. The bolt is normally spring-actuated in a clockwise direction and in such a position that the stud 17 bears against the left extremity of the slot 16, by means of a spring 26 coiled about the stud 17 and bearing against a casing stud 25 and an upstanding lug 34 of the bolt 10.

Figure 1 shows the locking mechanism engaging the shackle in fully locked position. The hook 15 of the lever 9 is shown engaging the slot 5' of the nose 5 of the shackle, while the hook 24 of the bolt 10 engages the same on the opposite side. The lug 12 of the lever 9 fits within a notch 14 of the bolt to guard against accidental relative movement of the two locking elements.

As the key 32 is fitted on the key stud 100 30 and rotated to the position shown in Figure 2, the lower ward 33' has engaged the bearing surface 23 of the lever 9, rotating the latter in a counterclockwise direction against the action of the spring 21 105 and out of engagement with the nose of

the shackle. Up to this point the bolt 10 has its hook engaging the nose of the shackle while its other end 27 bears against the projection 6 of the heel 4 of the shackle in 5 virtually locked relation. The lever having been thus rotated, its lug 12 has been withdrawn from the notch 14 of the bolt.

The bearing surface 18 of the bolt merely acts as a guide for the ward 33 of the key. 10 The other bearing surface 19 of the bolt is in a lower plane with an offset 20 there-between. Figure 2 shows the key touching the offset 20. Upon further rotation of the key, the ward 33 bearing against the offset 15 20, forces the bolt 10 to the right and the hook 24 out of engagement with the nose of the shackle; the hook 28 out of engagement with the stud 11; and the end 27 out of engagement with the heel of the shackle, 20 as the bolt slides to the right and pivots slightly on the stud 17 under the action of the spring 26.

This renders the shackle free from the locking elements and the nose removable 25 from the casing. In order, however, to make the release of the nose more positive upon the unlocking of the shackle, there is provided a spring 29 coiled about the stud 25 and bearing against the casing, the 30 other end of the spring fitting behind the projection 6 to accomplish the desired result.

As a further expedient to avoid disarrangement and malfunction of the two main locking elements, there is arranged there- 35 between a thin stationary change plate 8. This change plate has an aperture 11' to receive the stud 11, a notch 17' to receive the stud 17, and a recess 25' to receive the stud 25, thus separating the body portions 40 of the two locking elements 9 and 10.

In connection with the operation of the locking mechanism, the stud 11 is formed with a sharp corner extension 37 which affects the engagement of the hook 28 to more 45 accurately time and make simultaneous the engagement of the shackle by the bolt and lever. It will be understood from the foregoing description that, in locking the assembly, the toe of the shackle pushing down 50 on the hooked portion 28 of the bolt 10 causes the hook 28 to finally pass the lower pointed surface of the stud 11 and at this instant the spring 26 forces the bolt forward to securely engage the stud. The 55 mechanism cannot be locked until this operation is completed and the action of this hook 28 against the stud 11 withholds the entire mechanism from going into its locked position until the shackle pushes the bolt 60 down far enough so that both the bolt and lever are timed to enter the notch in the toe of the shackle simultaneously.

What I claim is—

1. A padlock comprising a casing, a 65 shackle, and a pair of locking units, said

shackle having its heel pivoted and its toe free to be inserted in said casing, one of said locking units comprising a lever pivoted on a stud and normally spring actuated to engage the toe of said shackle, the 70 other locking unit comprising a bolt slidably and pivotally mounted on a single stud and adapted to engage the toe and heel of said shackle in locking relation, said bolt having a hook member adapted to engage the stud on which said lever is pivoted, a stationary change plate interposed between the main body portions of said lever and bolt, said lever and bolt being adapted to be actuated respectively and in sequence by 75 the rotation of a key to release the lever from the toe and the bolt from the toe and heel and from the stud on which said lever is pivoted.

2. A padlock comprising a casing, a 80 shackle, and a pair of locking units, said shackle having its heel pivoted and its toe free to be inserted in said casing, one of said locking units comprising a lever pivoted on a stud and normally spring actuated to engage the toe of said shackle, the 85 other locking unit comprising a bolt slidably and pivotally mounted on a single stud and adapted to engage the toe and heel of said shackle in locking relation, said bolt having a hook member adapted to engage the stud on which said lever is pivoted, a stationary change plate interposed between the main body portions of said lever and bolt, said lever and bolt being adapted to be actuated respectively and in sequence by 90 the rotation of a key to release the lever from the toe and the bolt from the toe and heel and from the stud on which said lever is pivoted, 95

3. A padlock comprising a casing, a 100 shackle, and a pair of locking units, said shackle having its heel pivoted and its toe free to be inserted in said casing, one of said locking units comprising a pivoted lever normally spring-actuated to engage the toe 105 of said shackle, the other locking unit comprising a slotted bolt slidably and pivotally mounted on a single stud and adapted to engage both the toe and heel of said shackle in locked relation, said lever and bolt having bearing surfaces adapted to be engaged in sequence by a key for disengaging said lever from the shackle toe and said bolt from said toe and said heel, respectively, 110 said bolt having a pair of spaced notches, a lug carried by said lever and adapted to engage one of said notches when the assembly is locked, and the other notch when unlocked for the purpose of preventing relative movement of said lever and bolt in 115 120 125 130

either instance until said lever is actuated either by key or shackle.

4. A padlock comprising a casing, a shackle, and a pair of locking units, said shackle having its heel pivoted and its toe free to be inserted in said casing, one of said locking units comprising a lever pivoted on a stud and normally spring actuated to engage the toe of said shackle, the other locking unit comprising a bolt slidably and pivotally mounted on a single stud and adapted to engage the toe and heel of said shackle in locking relation, said bolt having a hook member adapted to engage the stud on which said lever is pivoted, a stationary change plate interposed between the main body portions of said lever and bolt, said lever and bolt being adapted to be actuated respectively and in sequence by the rotation of a key to release the lever from the toe and the bolt from the toe and heel and from the stud on which said lever is pivoted, said bolt having a pair of spaced notches, a lug carried by said lever and adapted to engage one of said notches when the assembly is locked and the other notch when unlocked for the purpose of preventing relative movement of said lever and bolt in either instance until said lever is actuated either by key or shackle.
5. A padlock comprising a casing, a shackle, and a pair of locking units, said shackle having its heel pivoted and its toe free to be inserted in said casing, one of said locking units comprising a lever pivoted on a stud and normally spring actuated to engage the toe of said shackle, the other locking unit comprising a bolt slidably and pivotally mounted on a single stud and adapted to engage the toe and heel of said shackle in locking relation, said bolt having a hook member adapted to engage the stud on which said lever is pivoted a stationary change plate interposed between the main body portions of said lever and bolt, said lever and bolt being adapted to be actuated, respectively, and in sequence by the rotation of a key to release the lever from the toe and the bolt from the toe and heel and from the stud on which said lever is pivoted, a spring bearing against said casing and said heel, by means of which the toe is under pressure to be positively ejected upon the release of said locking elements from said shackle, said bolt having a pair of spaced notches, a lug carried by said lever and adapted to engage one of said notches when the assembly is locked, and the other notch when unlocked for the purpose of preventing relative movement of said lever and bolt in either instance until said lever is actuated either by key or shackle.

6. A padlock comprising a casing, a pivoted shackle, and a pair of locking elements superimposed one upon the other with a

stationary change plate therebetween, means carried by one of said locking elements for coacting with the other to prevent relative lateral movement of said elements when they are in locked and unlocked position. 70

7. A padlock comprising a casing, a pivoted shackle, and a pair of locking elements superimposed one upon the other with a stationary change plate therebetween, means carried by one of said locking elements for 75 coacting with the other to prevent relative lateral movement of said elements when they are in locked and unlocked position, said means being releasable from locked engagement only upon the actuation of the element 80 carrying the same.

8. A padlock comprising a casing, a pivoted shackle, and a pair of locking elements superimposed one upon the other with a stationary change plate therebetween, means 85 carried by one of said locking elements for coacting with the other to prevent relative lateral movement of said elements when they are in locked and unlocked position, both of said elements being adapted to engage the 90 toe and one of said elements being adapted to engage the heel of said shackle, said elements being operable separately and in sequence by a single key to release first one element from the toe and the other element 95 from said toe and heel, respectively.

9. A padlock comprising a casing, a pivoted shackle, and a pair of locking elements superimposed one upon the other with a stationary change plate therebetween, means 100 carried by one of said locking elements for coacting with the other to prevent relative lateral movement of said elements when they are in locked and unlocked position, said means being releasable from locked engagement only upon the actuation of the element 105 carrying same, both of said elements being adapted to engage the toe, and one of said elements being adapted to engage the heel of said shackle, said elements being operable separately and in sequence by a single key to release first one element from the toe and the other element from said toe and heel, respectively, and a positive spring release for said shackle when in unlocked position. 110

10. A padlock comprising a casing, a pivoted shackle, and a pair of locking elements, both of said elements being adapted to engage the toe and one of said elements being 115 adapted to engage at its one end the heel of said shackle and at its other end a stationary member of said casing all in locked relation, said elements being operable separately and in sequence by a single key to release first one element from the toe and then the other element from the toe, from the stationary member of said casing, and from the heel of said shackle, respectively. 120

11. A padlock comprising a casing, a piv- 130

oted shackle, and a pair of locking elements superimposed one upon the other with a stationary change plate therebetween, both of said elements being adapted to engage the 5 toe and one of said elements being adapted to engage, at its one end, the heel of said shackle and at its other end a stationary member of said casing all in locked relation, said elements being operable separately and 10 in sequence by a single key to release first one element from the toe and then the other element from the toe, said stationary member of the casing, and the heel of said shackle respectively, means carried by one of said locking elements for coacting with the other to prevent relative lateral movement of said elements when they are in 15 locked and unlocked position, said means being releasable from locked engagement only upon the actuation of the element carrying same.

12. A padlock comprising a casing, a piv- 20 oted shackle, and a pair of locking elements superimposed one upon the other with a stationary change plate therebetween, both of said elements being adapted to engage the toe and one of said elements being adapt- 25 ed to engage, at its one end, the heel of said shackle and at its other end a stationary member of said casing all in locked relation, said elements being operable separately and

in sequence by a single key to release first one element from the toe and then the other 30 element from the toe, said stationary member of the casing, and the heel of said shackle respectively, means carried by one of said locking elements for coacting with the other to prevent relative lateral move- 35 ment of said elements when they are in locked and unlocked position, said means being releasable from locked engagement only upon the actuation of the element carrying same. 40

13. A padlock comprising a casing, a pivoted shackle and a pair of locking elements, both of said elements being adapted to engage the toe and one of said elements being adapted to engage, at its one end the 45 heel of said shackle and at its other end a stud all in locked relation, said stud being angular in its contour and of such dimensions and so arranged with respect to said bolt, that the shackle upon downward pres- 50 sure upon said bolt is engageable in locked relation upon and subsequent to the locked engagement of said bolt with said stud.

In testimony whereof I affix my signature.

SAMUEL R. FRAIM.
